UNITED STATES PATENT OFFICE

146,766

DESIGN FOR A SUIT

Mario Frascino, New York, N. Y.

Application November 13, 1946, Serial No. 134,761

Term of patent 3½ years

(Cl. D3—4)

To all whom it may concern:

Be it known that I, Mario Frascino, a citizen of the United States of America, residing in New York city, county of New York, and State of New York, have invented a new, original, and ornamental Design for a Suit, of which the following is a specification, reference being had to the accompanying drawing, forming part thereof, wherein,

I claim:

The ornamental design for a suit, substantially as shown.

MARIO FRASCINO.
